Mr. Douglass

ATTORNEY.

UNITED STATES PATENT OFFICE

96,450

DESIGN FOR A COMBINED REFRIGERATOR TRAY AND CONTAINER UNIT

Charles Daum, Forest Hills, N. Y.

Application February 6, 1935, Serial No. 55,271

Term of patent 3½ years

To all whom it may concern:

Be it known that I, Charles Daum, a citizen of the United States and a resident of No. 35 Nome Street, Forest Hills, Long Island, N. Y., with a post-office address at No. 39-40 Twenty-second Street, Long Island City, New York, have invented a new, original, and ornamental Design for a Combined Refrigerator Tray and Container Unit, of which the following is a specification, reference being had to the accompanying drawing, forming part hereof, in which

Figure 1 is a perspective view of the combined refrigerator tray and container unit showing my design as assembled.

Figure 2 is a perspective view of the tray portion of the design.

I claim:

The ornamental design for a combined refrigerator tray and container unit, as shown and described.

CHARLES DAUM.
